LENS STRAP FOR OPHTHALMIC MOUNTINGS

Bert J. Lowres, East Orange, N. J.

Application June 13, 1939, Serial No. 278,850

2 Claims. (Cl. 88—47)

This invention relates to improvements in lens straps for ophthalmic mountings.

This invention has for its objects to provide a novel strap means for attaching rimless mountings to lenses, whereby the operations of assembling and fastening a lens in connected relation to the mounting is greatly facilitated, while at the same time furnishing a strap structure and associated lens fastening means of such novel form and cooperative association that the outwardly presented face of said strap structure is unblemished by exposed portions of the associated lens fastening means, but rather whereby the latter are completely concealed, and the surface 15 of the outwardly presented face of the strap structure is left either smooth and unbroken or subject to engraved ornamentation of any desired design and character.

Another object of the invention is to provide a novel lens anchoring stud and means for interlocking the same to the inner face portion of the outwardly presented arm of the strap structure, whereby the stud may be first assembled with a lens by insertion in the eye or attachment 20 opening of the latter, and then such assembly slid between and into the embrace of the strap arms while at the same time interlocking the stud to the outer arm, whereupon the thus assembled parts may be secured together by a fastening 25 screw adapted to pass through the perforate inner strap arm into threaded engagement with said stud.

Other objects of this invention, not at this time more particularly enumerated, will be understood 30 from the following detailed description of the same.

An illustrative embodiment of this invention is shown in the accompanying drawing, in which:

Fig. 1 is a fragmentary front face view of an ophthalmic mounting and lens attached thereto by means of the novel strap structure according to this invention; Fig. 2 is a sectional view through the lens, taken on line 2—2 in Fig. 1, showing the structure in elevation, said view being drawn on an enlarged scale; Fig. 3 is a fragmentary top edge view of the assembled lens and strap structure; Fig. 4 is a longitudinal horizontal section, taken on line 4—4 in Fig. 1, but drawn on an enlarged scale; Fig. 5 is a vertical longitudinal section, taken on line 5—5 in Fig. 3; and Fig. 6 is a longitudinal horizontal section of the parts as disposed preparatory to assembling.

Similar characters of reference are employed in the above-described views, to indicate corresponding parts.

Referring to the drawings, the novel strap structure comprises a bifurcate member formed by spaced apart front and rear strap arms 10 and 11 joined at their rearward ends by a butt portion 12 adapted to extend across the edge of a lens L to which the strap structure is applied. Extending upwardly and downwardly respectively from said butt portion 12, in the plane of the lens edge, are the upper and lower abutment lugs or members 13 and 14, by which the edge of the lens L, as embraced by the strap structure, is supported so as to hold the lens against rocking displacement or play. Suitably attached to and extending from the exterior portion of said butt portion 12 are desired elements of a rimless 15 ophthalmic mounting, such e. g. as a center piece or bridge 15 and a supporting arm 16 by which the nose-pad or guard 17 is carried. It will be understood that other elements of a mounting, such as temple end pieces, etc. (not shown), may 20 be supported from a strap structure according to this invention, where the mounting is of a type requiring or including such elements.

The front strap arm is provided in its inner face portion with a recess or chamber 18 behind 25 its outer face portion and open endwise toward the free end of said strap arm, said chamber being bounded on its lens facing side with spaced upper and lower flanges 19 and 20, the opposed free margins of which define a slot-way 21. The 30 interior end of said recess or chamber 18 is terminated by a stop shoulder 22.

The reference character 23 indicates a stud member having an axial internally screw-threaded bore 24, and being further provided at 35 one end with an enlarged, flat plate-like head 25 of a thickness corresponding to the space dimension of the recess or chamber 18 intermediate the outer face portion of the strap arm 10 and the flanges 19—20. Said stud member 23 is 40 adapted for insertion through an eye or attachment opening 26 with which the lens L is provided; said stud being entered in said opening 26 from the front face of said lens so that the head 25 of the stud member is disposed adjacent said 45 front face.

The rear strap arm 11 is provided with an opening 27, preferably having a countersunk seat 28 at its outer end. A fastening screw 29 is insertable through said opening 27, and is provided with a slotted head 30 to engage said seat 28.

To assemble a lens L and the novel strap structure together, the stud member 23 is first inserted in the eye or attachment opening 26 55

of the lens as above described, and as shown in Fig. 6, whereupon the butt edge of the lens is opposed to the space S (see Fig. 6) intermediate the strap arms 10 and 11; the stud member 23 being so disposed as to align its head 25 with the open end of the recess or chamber 18. This having been done, the lens L is thrust endwise (in the direction of the arrow x in Fig. 6), thereby entering the butt edge of the lens in the space 10 S between the strap arms 10 and 11 until stopped against the abutment lugs or members 13—14, while at the same time the head 25 of the stud member 23 is moved into the recess or chamber 18 and beneath the flanges 19—20; the shank of 15 said stud member passing freely through the slot-way 21 between said flanges. In this manner the stud member and front strap arm 10 are interlocked together, and the bore 24 of the former is brought into alignment with the opening 20 27 of the opposite strap arm 11. The parts as thus assembled are thereupon secured against separation by screwing home the fastening screw 29, which is passed through the opening 27 of strap arm 11, and screwed into the internally 25 threaded bore 24 of the stud member 23. Preferably said head 25 of the stud member 23 is of polygonal peripheral shape, whereby engagement thereof with the sides of the recess or chamber 18 will retain the stud member 23 against rotation when the fastening screw 29 is driven home 30 therein. In this manner, the respective strap arms 10 and 11 are securely tied one to the other through the intermediate stud member 23, and brought into firmly embracing relation to the 35 opposite faces of the lens L, while the latter is anchored against outward displacement from such relation by the stud member's engagement therewith through the eye or attachment opening 26.

40 It will be obvious that a very simple and easily manipulatable lens attaching and holding means is provided by the novel strap structure; while, at the same time, the front or exposed face of the outer strap member is in no way defaced by 45 exposure of fastening screws, rivets or like fastening means, since the stud member 23 is interlocked with said outer strap arm 10 in such manner as to be wholly concealed, while nevertheless in a manner providing a secure and efficient interlocked attachment thereto.

50 It will be understood that various changes could be made in the novel strap structure of this invention without departing from the scope

of the invention as defined by the following claims. It is therefore intended that all matter contained in the above description or shown in the accompanying drawing shall be interpreted as illustrative and not in a limiting sense.

I claim:

1. A lens strap structure for ophthalmic mountings comprising, spaced rigid strap arms to receive a lens therebetween, the rearwardly presented strap arm having an opening therethrough, the outwardly presented strap arm having an endwise open recess at the back thereof, a stud member having an internally screw-threaded bore insertable into the attachment opening of the lens so as to be carried by said lens, said stud member being of a length less than the thickness of the lens, said stud member having at one end an enlarged head of polygonal shape adapted to slidably enter said recess when the lens carrying said stud member is inserted between said spaced strap arms, whereby said head is embraced and held by the sides of said recess to thereby retain said stud member against rotative displacement, and a headed fastening screw adapted to be passed through the opening of said rearwardly presented strap arm to screw into the bore of said stud member.

2. A lens strap structure for ophthalmic mountings comprising, spaced front and rear rigid strap arms to receive a lens therebetween, the rear strap arm having an opening therethrough, the front strap arm having an endwise open recess bounded by front and rear face walls, the rear face wall of which is provided with an endwise open slot-way laterally open to said recess, a stud member having an internally screw-threaded bore and a head of polygonal shape at one end, said stud member being carried in the attachment opening of the lens and extending from the outer face side of the latter so as to dispose said head adjacent thereto, said head being adapted to enter said recess and the stud member through said slot-way when the lens carrying said stud member is inserted between the strap arms, whereby said head is embraced by said front strap arm recess so as to hold the same and said stud member against rotation while at the same time concealing said head behind the front face wall of said front strap arm, and a fastening screw adapted to be passed through the rear strap arm opening to screw into the bore of said stud member.

BERT J. LOWRES.
